223,035

NURSERY GYM

Irving Brecher, 5 Greenacre Court,
Great Neck, N.Y. 11021

Filed Oct. 6, 1970, Ser. No. 25,355

Term of patent 14 years

Int. Cl. D21—01

U.S. Cl. D34—15

FIG. 1

FIG. 2

FIG. 3

FIG. 4

FIG. 1 is a top plan view of my new design for a nursery gym;

FIG. 2 is a side elevational view thereof, the side not shown being identical thereto;

FIG. 3 is an end elevational view thereof, the end not shown being identical thereto; and

FIG. 4 is a bottom plan view thereof.

Portions of FIGS. 2 and 3 are shown fragmentarily for convenience of illustration.

I claim:

The ornamental design for a nursery gym, substantially as shown and described.
